[57] CLAIM

The ornamental design for a facsimile transceiver, as shown and described.

DESCRIPTION

FIG. 1 is a top, front and right side perspective view of a facsimile transceiver showing our new design, with the paper trays withdrawn;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a second embodiment of FIG. 1;

FIG. 9 is a front elevational view thereof;

FIG. 10 is a top plan view thereof;

FIG. 11 is a right side elevational view thereof;

FIG. 12 is a left side elevational view thereof;

FIG. 13 is a rear elevational view thereof; and,

FIG. 14 is a bottom plan view thereof.
